PAPER BOARD SHIPPING CONTAINER OR CARTON

Application filed March 3, 1930. Serial No. 432,976.

This invention relates to paper containers or cartons designed for the shipment of goods and which are liable to exposure to the weather either during shipment or before the contents are removed. For instance, in the shipment of white tile such as are used for lining bath room walls, it sometimes occurs that such cartons are exposed to rain or are otherwise wetted and this results in a discoloration of the contents. To remedy this defect, I have devised a construction, which, even when soaked with water for a considerable period of time, will have no detrimental effect on the contents, as hereinafter set forth, and shown in the drawing in which Figure 1 is a perspective view of the container; Figure 2 is a horizontal section through a corner portion thereof.

My invention is based on the discovery of certain conditions in paper cartons as usually manufactured which are incidental to the process of manufacture and the materials used in manufacture. Thus one prominent grade of shipping containers is made from corrugated board which is a combination of corrugated unsized straw paper, or other grades of paper, usually of .009 inch caliper, and liner board, which usually calipers .016 inch. The adhesive used is silicate of soda, although other adhesives may be satisfactorily employed. The straw paper is manufactured from wheat, rye, oat, or other grades of straw by cooking them in digesters under steam pressure with an aqueous solution of lime, caustic soda, soda ash, sulphide of soda, or a combination of these alkalis, and then subjecting the cooked material to the well known paper making process. The liner board is made largely from old papers. On the surface of the liner board is incorporated a layer of first use kraft pulp. The manufacture of this board is made on a multi-cylinder type paper machine in accordance with the well known art. The kraft pulp is usually colored by means of coal tar dyestuffs which are fixed on the fiber by the well known application of rosin size and alum. The silicate of soda is manufactured by fusing at a relatively high temperature sand and soda ash, and as a commercial product, silicate of soda,

in solution, as used on the corrugating machines, contains an appreciable amount of strong alkali which is probably present in the form of caustic soda.

When shipping containers, made by combining the above mentioned unsized straw paper, liner board, dyestuffs, and silicate of soda, are soaked in or otherwise subjected to the action of water, the water becomes discolored. If the contents of the shipping container are of such a nature that they absorb or are otherwise affected by coloring materials, although not necessarily injured by water alone, they would be appreciably damaged if acted upon in this manner. For example, if the white tile previously referred to were shipped in a corrugated container of the usual type and it were soaked in water, the coloring matter from the box would impregnate the unglazed portion of the tile, work its way through the interior of the tiles and ultimately cause a discoloration immediately under the glazed exterior surface, which would render this product unfit for use. In setting these tiles the regular practise is to immerse the box and contents in water and then apply the tile with plaster to the wall in the usual manner. If during this operation, the work should be interrupted and the tile in the box should remain immersed for several hours, as for instance, over night, the tile would develop this discoloration.

I have discovered that the liner board if uncolored when soaked in clean water will not discolor the water and therefore will not injure the contents, but if there is present any dyestuff not entirely fast to water or any free alkali then discoloration takes place. Thus if in the manufacture of the carton silicate of soda is used as the adhesive, discoloration is liable to take place. I have further discovered that if the container formed of straw board is soaked with water it also will produce a discoloration. Thus cartons as usually manufactured may injure the contents from either of these causes.

To overcome this defect, I employ in the manufacture of cartons a straw paper board which is either free from dyestuff soluble in

water, or which is sufficiently water repellent to prevent the dissolving out of dyestuffs contained therein. Thus I have found straw paper sized with approximately 1% more or less of rosin size and sufficient alum to effect its precipitation acquires water repellent properties which enables it to resist water for long periods, as for instance, over night, and that such straw paper does not discolor clean water. I have further discovered that if colorless adhesive which is free or nearly free from alkali is used in the manufacture of the carton, no discoloration will take place as an incident to wetting. Based upon these discoveries, my improved carton is formed from a straw paper board which of itself will not discolor water and which in its manufacture is cemented by a colorless adhesive free or nearly free from alkali, such as starch paste. More specifically, my improved carton is one formed from sized straw paper board such as above referred to cemented by such a colorless adhesive free or nearly free from alkali, as starch paste. It is obvious however, that various other specific materials may be substituted, both in the manufacture of the board and the adhesive, the essential feature being that the completed structure when soaked with water will not produce any discoloration.

As specifically shown in the drawing, A is the outer container which is formed of double faced corrugated straw paper board B originally containing water soluble coloring matter but which has been rosin sized to render the same water resilient, as diagrammatically indicated by the heavy lines C. D is the liner or internal structure for dividing the space within the container into separate compartments E for receiving the individual tiles and protecting the same from each other. This liner is formed from a paper board which is free from water soluble coloring matter and thus as previously described the container may be soaked in water without danger of dissolving out any coloring matter which will discolor or injure the contents.

What I claim as my invention is:

1. A package comprising a content of tile or the like subject to discoloration when allowed to stand in colored water and a paper board shipping container for said tile free from accessible coloring matter soluble on immersion in water.
2. A package comprising a content of tile or the like subject to discoloration when allowed to stand in colored water and a shipping container therefor composed in part of paper free from soluble coloring matter and in part from paper containing soluble coloring matter rosin sized to be water repellent.
3. A package comprising a content of tile or the like subject to discoloration when allowed to stand in colored water, and a ship-

ping container therefor formed of a corrugated paper board free from accessible coloring matter soluble on immersion in water and a non-alkaline colorless adhesive.

4. A package comprising a content of tile or the like subject to discoloration when allowed to stand in colored water, and a shipping container therefor composed in part of a paper which of itself will discolor water, rosin sized to be water repellent and a colorless non-alkaline adhesive.

In testimony whereof I affix my signature.
PIERRE DREWSSEN.
